PRESSER LID WITH STEAMING
ATTACHMENT

Harold D. Davis, Brooklyn, N. Y.

Application June 22, 1949, Serial No. 100,569

1 Claim. (Cl. 38—3)

1

The purpose of my invention is to provide a new means of steaming the lid of the conventional pressing machine.

My invention also provides for the use of a syphon water spray from a bottle, which sprays water on a screen which covers the pressing surface.

Referring to the drawings which illustrate my invention

Figure 1 is a front elevation of presser lid with steaming attachment installed.

Figure 2 is a top plan view of the presser lid enlarged.

Figure 3 is a section taken on the line 3—3 of Figure 1.

Figure 4 is a section taken on the line 4—4 of Figure 1.

Figure 5 is a top plan view of the bottle clamp.

Figure 6 is a side elevation of the bottle clamp.

Figure 7 is a front elevation of the bottle clamp.

A presser lid or press head 1 in a conventional pressing machine, carries at its upper edge two brackets 2 riveted or otherwise fastened at either end of the lid. A rod or handle 3 is secured intermediate the brackets 2 and has slidably mounted to it a bottle clamp 4 which holds the bottle 5 rigidly. The lower edge of the lid 1 has a piano hinge 6 secured to it, to which is hinged a U frame 7 of approximately the shape of the lid. A piece of absorbing cloth is held taut in the frame 7 to provide a dampening screen. A knob 9 is secured to the flange 10 on the upper edge of the frame to facilitate pulling down from the lid. In order to retract the frame to the lid two springs 11 are mounted in recesses 12 in the lid and fastened to the frame at 13 thus allowing a quick return movement.

The clamp 4 is constructed with loops 14 which encircle the rod 3 and a depending end 15 tends to keep the clamp in a normal position as shown in Figure 3. Two arcs 16 extend upwardly from the loops 14 and encircle the front end of the neck 17 of the bottle 5. One of two further strut members 18 protrude horizontally from the loops 14 to the central coil 19 from which an arc 20 extends upwardly. This arc again terminates in a central coil 21 which in turn extends upwardly to form an arc 22. The arc 22 finally returns to form the strut 18. It will be seen that the clamp may be made of one piece of wire. The arc members 20 and 22 encircle the rear end of the bottle neck 17 thus clamping the bottle rigidly to hold it in position as shown in Figure 3.

2

The syphon lever 23 and the spout 24 allow the flow of the spray of water onto the cloth screen after the frame is pulled away from the lid as shown in Figure 4. The clamp may be slid along the length of the rod in order to get the spray on all parts of the cloth. The bottle may also be tilted to allow the spray of water to go lower onto the cloth. The depending end 15 of the clamp acting as a spring will return the bottle to normal position.

The lid is electrically heated by elements not shown, receiving current through the plug 25 which is attached to the end of the lid. A syphon spray of the character referred to in this application is described in Patent Number 2,326,641.

Although the drawings and specification disclose the best method in which I have embodied my invention, I desire in no way to be limited to the details of my disclosure for the reason that slight changes in form and proportion may be made without departing from the spirit of my invention within the broad scope of the appending claim.

What I claim as new and novel is:

25 In combination with a pressing machine having a pressing head provided with an upper longitudinal edge and adapted to be used with a pressing cloth, a steaming attachment comprising a pair of brackets secured to said upper longitudinal edge of said press head adjacent to the ends thereof, a rod secured to and extending intermediate of said brackets, a liquid container slidably carried by said rod, spray forming means carried by said container directed at the upper surface of said cloth whereby a spray of liquid 30 may be ejected from said container onto said pressing cloth upon the operation of said spray forming means.

HAROLD D. DAVIS.
